NELSON W. WEBB, OF BELLEVILLE, NEW JERSEY, ASSIGNOR TO EASTWOOD WIRE CORPORATION, OF BELLEVILLE, NEW JERSEY, A CORPORATION OF NEW JERSEY

WOVEN-WIRE BELT FOR PAPER-MAKING MACHINES AND METHOD OF FORMING THE SAME

Application filed March 5, 1929. Serial No. 344,307.

The present invention relates to woven wire belts particularly for paper-making machines of the Fourdrinier type, and methods of forming the same.

5 These belts are in the form of a continuous band including a transverse seam, where the two ends of the wire cloth are joined, and this seam should have substantially the same tensile strength, flexibility, and porosity as the 55 body of the wire, and should be free of any projecting ends or knuckles, or any portions or wire ends that might become projected during use of the belt. The seam should furthermore be substantially continuous with 60 15 the surface of the body of the wire at each side.

In addition to the detrimental effect that imperfections in the seam have upon the paper, there is also the chance of injuring the 20 body of the wire, rendering it unfit for further use. Wire belts of this type are usually of very fine weave, say 60 to 80 wires to the inch, and are of large dimensions, say 80 feet long and 20 feet wide, and in their use in the 25 paper machine move at great speed, say 1000 feet a minute. The fineness of the weave and the large size of the belt make the production of a suitable seam very difficult, and the extreme conditions of use put it to such severe 30 strains and stresses that a weak point or irregularity in the seam is apt to open up or stretch, with the result usually that the entire wire belt is spoiled for further use and must be discarded.

35 From the very nature of these wire belts they are very expensive and the extreme conditions of use make their period of usefulness relatively short, so that any appreciable increase in the life of the belt not only will result in a very great saving in the cost of manufacture of the paper produced upon the machine, but will reduce the number of times that the machine must be laid up for the installation of a new belt.

40 45 The seam is usually produced by a lacing wire that is hand-sewed about the end shoots of weft wire, this operation requiring great skill and deftness, because of the fineness of the weave and the necessity for exact uniformity in all parts of the seam. Obviously the

end weft wires are not as securely supported against longitudinal strain as the weft wires in the body of the wire cloth, and any shifting of these end weft wires will tend to spread or cam open the end portions of the warp 55 wires causing them to project beyond the surface of the belt. Various methods have been employed to secure them against the terrific strain they must undergo in use, but these have been unsatisfactory in practice for the 60 most part.

It is an object of the present invention to produce a wire belt in which the end weft wires are connected to the warp wires in such manner that said end weft wires will resist 65 longitudinal pulling strains equally at all points along the width of the belt, while at the same time every warp wire end will be securely held to the end weft wires against the tendency to spread beyond the surface of 70 the wire cloth, and further to provide such end weft wires of such dimensions that the lacing wire may be carried about them without increasing the thickness of the belt at the seam, and in such manner that the seam will 75 have substantially the same characteristics of strength, flexibility and porosity as the body of the cloth.

To this end it is proposed to provide end weft wires of elongated cross-section, substantially integrally joined to the warp wire ends, as by brazing, in such manner that the union between them extends over a relatively long junction area longitudinally of the warp 80 wires, and not only over the superimposed surfaces, but also over supporting or trussing areas surrounding the superimposed surfaces, so that the resistance to pulling strains is most effectually opposed to the direction of such strains.

85 According to the present embodiment of the invention the end weft wires are of slightly greater cross-sectional width than the diameter of the wires of which the cloth is woven, and are slightly less in thickness than the diameter of such wires. While I preferably propose to employ an end weft wire which in its first state of insertion in the belt is in the form of a plurality of circular cross-section wires, sheathed in a thin film or coat- 90 95 100

ing of brazing or hard solder, and in its final brazed state is an integral mass having the characteristics above outlined, I also propose to employ wires of one piece, as for instance of ribbon or oval cross-section, and also having these characteristics.

Another object is to provide an end weft wire which in connection with the warp wire ends will provide a structure which will be self-brazing upon the application of heat, and so arranged that the end weft wires and warp wire ends will be intimately joined and trussed along their superimposed and immediately adjacent surfaces, without producing uneven lumpy spots, and with perfect uniformity along the entire width of the belt.

In the production of wire belts of the present type it is practically impossible to exactly determine just which weft wire will constitute the end of a length of wire cloth for forming a belt of a given length, as the stretching and other operations, which the cloth undergoes after weaving, as well as varying conditions in the actual weaving, preclude such exact determination, it being borne in mind that in an 80-foot belt there may be approximately 70,000 weft wires.

It is also unsatisfactory to weave into the wire cloth, while in the loom, a weft wire having different characteristics of shape or consistency from the regular weft wires, as a different characteristic would be imparted to the warp wires at this point due to the actions of the heddles and lay, and which might in some cases impair the body of the cloth rendering it unfit for paper making machine use.

It is therefore proposed as a further object of the invention to provide an end weft wire, having different characteristics from the regular weft wires, and which may be inserted in the cloth in substitution of and to replace one of the regular weft wires, removed for the purpose, and which will furthermore not injure or impair the structure and uniformity of the cloth.

Another object is to provide end weft wires about which the lacing wire may be directly engaged, and which will so support it that the tendency to bow and project beyond the surface of the cloth will be obviated, assuring a firm, uniform and flat seam.

A further object is to provide a seam which, because of the long contacting and joined areas of the end weft wires with the warp wire ends, will be particularly adapted for twill or other loose weave wire belts, where certain of the warp wires at the ends of the cloth may extend over or under two or more weft wires, and therefore are not ordinarily so firmly supported as the others.

With the above and other objects in view, embodiments of the invention are shown in the accompanying drawings, and these embodiments will be hereinafter more fully de-

scribed with reference thereto, and the invention will be finally pointed out in the claims.

In the drawings:

Fig. 1 is an enlarged plan view of a portion of the belt at the seam.

Fig. 2 is a longitudinal sectional view, taken along the line 2—2 of Fig. 1.

Fig. 3 is a further enlarged plan view of a portion of the end of the wire cloth as woven in the loom.

Fig. 4 is a longitudinal sectional view, taken along the line 4—4 of Fig. 3.

Fig. 5 is a plan view showing the wire cloth with several of the end weft wires removed.

Fig. 6 is a longitudinal sectional view, taken along the line 6—6 of Fig. 5.

Fig. 7 is a plan view showing the end seam forming weft wire inserted in the wire cloth, the projecting warp ends having been clipped off.

Fig. 8 is a longitudinal sectional view taken along the line 8—8 of Fig. 7.

Fig. 9 is an end edge view partly in elevation, and partly in section along the line 9—9 of Fig. 7.

Fig. 10 is a plan view showing the seam forming weft wire brazed to the warp wire ends.

Fig. 11 is a longitudinal sectional view taken along the line 11—11 of Fig. 10.

Fig. 12 is an end edge view, partly in elevation, and partly in section along the line 12—12 of Fig. 10.

Fig. 13 is an enlarged plan view of a portion of one end of a belt formed of twill weave wire cloth, and showing the same with the seam forming weft wire, according to the present invention, and before it is secured by the lacing wire to the other end.

Fig. 14 is a longitudinal sectional view taken along the line 14—14 of Fig. 13.

Fig. 15 is a view similar to Fig. 14, and showing a further modification in which two seam forming weft wires are inserted.

Figs. 16 and 17 are cross-sectional views of two modified forms of seam forming solder covered wires, one being of oval form and the other of ribbon form.

Figs. 18 and 19 are longitudinal sectional views of the end portion of a belt with these modified forms of seam forming wire brazed thereto.

Similar reference characters indicate corresponding parts throughout the several figures of the drawings.

Referring to the drawings, and more particularly to Figs. 1 to 12 thereof, Fig. 1 shows, greatly enlarged, a portion of the two ends of the wire cloth which are seamed together to form a belt, the portion as shown representing a piece of the belt which in its actual size is about $\frac{1}{16}$ of an inch in width. The wire cloth consists of warp wires 1 and weft wires 2 of brass, bronze, or other suitable material for the purpose. At each end of the length

of wire cloth several of the standard weft wires (three in the present embodiment), which have been woven in the loom, are removed, the wire being woven of slightly greater length than the length of the desired length of belt. In order to effectually remove these, and insert the end or seam forming wires, without injuring the body of the cloth, the first, second, and third shoots of standard

10 weft wire, indicated at *a*, *b*, and *c* in Fig. 3, are removed individually simply by pulling the same outwardly away from the warp ends from one longitudinal edge of the cloth to the other. The removal of the weft wires
 15 tends to spread the warp ends slightly as shown in Fig. 6, the knuckles at the point *c*, however, being substantially in their original relation, due to the springiness of the wire. The seam forming end weft wires are then
 20 inserted at the point *c* and the projecting ends of the warp wires are clipped off, before the brazing operation, as shown in Fig. 7, and as will be presently more fully pointed out.

The removal of the end weft wires produces
 25 at the point *c* a continuous straight passage transversely through the warp wires, as clearly shown in Fig. 6, this passage being slightly wider in the longitudinal direction of the cloth than the diameter of the removed wire,
 30 and also slightly wider, relatively to the thickness of the cloth, than the passage previously occupied by the removed wire.

The seam forming end weft wire 3, in the present embodiment, comprises a pair of solder covered wires 3^a and 3^b, formed of suitable material, as bronze or brass, the solder covering 3^c being preferably a hard or brazing solder, as for instance silver solder, and the diameters of these wires being such that
 40 they may be threaded through the transverse passage through the warp wires. In order to provide a final structure of the desired dimensions and cross-section, these wires are preferably of less diameter than
 45 the wires in the body of the cloth, while their combined width is slightly greater than the diameter of said body wires. The threading may be facilitated by brazing needle wires 4, of relatively stiffer metal, to the ends of the
 50 wires 3^a and 3^b, as shown in Fig. 7, the latter being then pulled through the passage. This threading operation takes place before the warp ends are clipped off so that there is no distortion of the warp ends at the point *c*. In
 55 order to more closely conform the surface of the seam forming wires to the surfaces of the warp wire ends, a grooved roller may be passed along the edge to slightly compress the warp ends, causing the seam forming
 60 wires to assume a slightly crimped shape, as shown in Fig. 12.

Heat is now applied to the edge of the wire cloth containing the wires 3^a and 3^b, which may first be coated with a suitable flux to facilitate the brazing action. The

adjacent weft wires are preferably shielded during this operation. As the heat is applied the solder flows by capillary action between the wires 3^a and 3^b and simultaneously to superimposed surfaces of the warp wire 70 ends, also spanning to points upon the warp wires slightly removed from the wires 3^a and 3^b to form trussing portions, as indicated at 3^d.

The two points at which the wires 3^a and 3^b contact with the warp wires before brazing, and the relatively wide upper and lower surfaces of two wires, not only insures a large junction area between the wires 3^a and 3^b and the warp wire ends, but so relates the adjacent surfaces that a capillary flow of the metal takes place between the two wires 3^a and 3^b to integrally join them, and between these wires and the warp wire ends to integrally join and truss them, the interstices between the wires being at the same time maintained uniformly free of lumpy spots, because of the capillary flow of the metal away from them. This is clearly indicated in Figs. 10, 11
 90 and 12.

The seam is now completed by hand-sewing the lacing wire 5 about the two butted ends of the length of wire cloth, this lacing wire being preferably of slightly smaller diameter than the diameter of the warp and weft wires 1 and 2, so that it will not project beyond the surfaces of the belt. By way of example I have shown this lacing wire sewed directly about the end weft wires 3 and engaged through alternate interstices at each side, but it will be understood that any desired form of lacing may be employed, and in certain instances may be carried about the adjacent weft wires 2. Also in certain instances it may be desirable to provide two or more brazed-in wires 3, instead of the single end wire, as shown, and my invention contemplates such a construction.

The brazed-in wires 3, because of their relatively thin cross-section, do not increase the thickness of the cloth at the end, while their relatively wide substantially flat surfaces provide a firm support for the lacing wire, so that the tendency to bow, as would be the case with a circular cross-section larger-diameter end wire, is effectually prevented. The elongation of the cross-section of the wire 3 longitudinally of the belt provides a seam which will most effectually and uniformly oppose the great strain imposed during use of the belt, and the warp wire ends are furthermore securely held against spreading or camming open, so that the chance of damage to the paper or the belt from this cause is eliminated.

In Figs. 13 and 14 I have shown the embodiment of my invention in a belt in which the weave is of the twill type, and in which the warp threads 1 are carried over one and under two of the weft threads, while the weft
 110

threads 2 are carried over two and under one of the warp threads. Obviously the warp ends have different relations to the end weft wire, certain of them being carried over it and under the next weft wire, others being under it and over the next weft wire, and still others being carried under it and also under the next weft wire, so that there is a greater tendency for these latter ends to spread. The end weft wire 3, according to my invention, is particularly suited to this condition, because of the relatively long junction point with the warp wire ends, which stiffens the loose warp ends against bowing or bending away from the belt surface, and the secure connection of these ends with the end weft wire. In the modification shown in Fig. 15 two of the weft wires 2 are removed at the end, and two seam forming wires 3 inserted and brazed in, thus securing the long crimps at two points.

In Figs. 16 and 18 I have shown a single solder covered end weft wire 6 of substantially oval cross-section, and in Figs. 17 and 19 I have shown a single solder covered wire 7 of flat or ribbon-like cross-section. These wires are adapted to be inserted in the same manner as the two wires 3^a and 3^b, and in their final brazed form have substantially the same relation in the belt.

I have illustrated and described preferred and satisfactory embodiments of my invention, but it will be obvious that changes may be made therein within the spirit and scope thereof, as defined in the appended claims.

Having thus described my invention what I claim and desire to secure by Letters Patent is:—

1. In a wire cloth belt, a length of woven wire cloth, a weft strand at each end thereof engaged with the warp wire ends and having a cross-section elongated longitudinally of the cloth, and means connecting the ends of said cloth together to form a belt.

2. In a wire cloth belt, a length of woven wire cloth, a weft strand at each end thereof engaged with the warp wire ends and having a cross-section elongated longitudinally of the cloth and connected to said warp wire ends by a metallic junction, and means connecting the ends of said cloth together to form a belt.

3. In a wire cloth belt, a length of woven wire cloth, a weft strand at each end thereof engaged with the warp wire ends and connected thereto by a metallic junction elongated relatively to the length of the warp wires, and means connecting the ends of said cloth together to form a belt.

4. In a wire cloth belt, a length of woven wire cloth, a weft strand at each end engaged with the warp wire ends thereof and having a cross-section elongated longitudinally of the cloth, and connected to said warp wire ends by a metallic junction, and a lacing wire engaged about said end weft strands and

connecting the ends of said cloth together to form a belt.

5. In a wire cloth belt, a length of woven wire cloth, a weft strand at each end engaged with the warp wire ends thereof and having a cross-section elongated longitudinally of the cloth and connected to said warp wire ends by a metallic junction coextensive with the superimposed areas of said end weft wires and said warp wire ends and extending beyond said superimposed areas of said warp wire ends, and means connecting the ends of said cloth together to form a belt.

6. In a wire cloth belt, a length of woven wire cloth, a replacement weft strand at each end having a laterally elongated cross-section and engaged with the warp wire ends thereof in substitution of a removed and previously woven-in weft strand having a circular cross-section, and means connecting the ends of said cloth together to form a belt.

7. In a wire cloth belt, a length of woven wire cloth, a weft strand at each end engaged with the warp wire ends thereof and comprising a plurality of juxtaposed wires connected together along their entire length by brazing and connected to said warp wire ends by brazing, and means connecting the ends of said cloth together to form a belt.

8. In a wire cloth belt, a length of woven wire cloth, a weft strand at each end engaged with the warp wire ends thereof and comprising a plurality of juxtaposed wires of a diameter smaller than the diameter of the other weft wires, connected together along their entire length by brazing, and connected to said warp wire ends by brazing, and means connecting the ends of said cloth together to form a belt.

9. In a wire cloth belt, a length of woven wire cloth, a weft strand at each end engaged with the warp wire ends thereof and comprising a plurality of juxtaposed solder covered wires connected together along their entire length by brazing and connected to said warp wire ends by brazing, and means connecting the ends of said cloth together to form a belt.

10. The method of forming a wire cloth belt, which comprises providing weft strands having an elongated cross-section at each end of a length of wire cloth, brazing said weft strands to the warp wire ends along junction areas elongated longitudinally of the warp wires, and securing the two ends of the cloth together by a lacing wire to form a seam.

11. The method of forming a wire cloth belt, which comprises providing weft strands at each end of a length of wire cloth, each consisting of a plurality of solder covered wires, brazing said plurality of wires together along their length to form an integral strand having an elongated cross-section, brazing said weft strands to the warp wire

ends, and securing the two ends of the cloth together by a lacing wire to form a seam.

12. The method of forming a wire cloth belt, which comprises providing weft strands at each end of a length of wire cloth, each consisting of a plurality of solder covered wires, brazing said plurality of wires together along their length to form an integral strand having an elongated cross-section, brazing said weft strands to the warp wire ends simultaneously with the brazing together of said solder covered wires, and securing the two ends of the cloth together by a lacing wire to form a seam.

15 Signed at Belleville, county of Essex, and State of New Jersey, this 26th day of February, 1929.
